(57) **CLAIM**

The ornamental design for a lighted computer pole tree having swiveling/adjustable shelves, power strip and phone jack, as shown and described.

DESCRIPTION

FIG. 1 is a perspective view of a lighted computer pole tree having swiveling/adjustable shelves, power strip and phone jack showing our new design;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof; and,

FIG. 6 is a bottom plan view thereof.

The broken lines show environmental structure for illustrative purposes only and form no part of the claimed design.
